UNITED STATES PATENT OFFICE.

EDWIN A. STRATTMAN, OF BOGALUSA, LOUISIANA.

JORDAN-PLUG FILLING.

Application filed October 16, 1922. Serial No. 594,793.

To all whom it may concern:

Be it known that I, EDWIN A. STRATTMAN, a citizen of the United States, residing at Bogalusa, in the parish of Washington and State of Louisiana, have invented certain new and useful Improvements in Jordan-Plug Fillings; and I do declare the following to be a full, clear, and exact description of the invention, such as will enable others skilled in the art to which it appertains to make and use the same.

My invention relates to improvements in machines for grinding paper pulp and has reference more particularly to the rotary grinding members commonly known as Jordan plugs. Plugs of this character are provided with grinding ribs or the like carried by a removable sleeve or "filling," which surrounds the plug and is necessarily removed from time to time, for well-known reasons. It is the object of my invention to provide a simple and inexpensive, yet highly efficient and reliable means for removably securing the covering sleeve upon the plug, the construction being such that while an effective driving connection is provided between the plug and its covering sleeve, this sleeve may be quickly and easily removed whenever desired.

With the foregoing in view, the invention resides in the novel subject matter hereinafter described and claimed, the description being supplemented by the accompanying drawings.

Fig. 1. is a side elevation of a Jordan plug, and its covering sleeves secured in assembled relations in accordance with my invention.

Fig. 2. is an end elevation.

Fig. 3. is a transverse sectional view as indicated by line 3—3 of Fig. 1.

Fig. 4. is a perspective view of a portion of the Jordan plug covering sleeve.

Fig. 5. is a longitudinal sectional view of the parts shown in Fig. 1.

Fig. 6. is a perspective view of one of the annular plates used in securing the covering sleeve upon the plug.

Fig. 7. is a side elevation showing a slightly different form of construction.

Fig. 8. is a transverse section on line 8—8 of Fig. 7.

Fig. 9. is a side elevation showing a still further form of construction.

In the drawings above briefly described, the numeral 1 designates a tapered Jordan

plug of circular cross section, said plug being mounted upon the Jordan shaft 1' in a suitable manner. The plug 1 tapers gradually toward one end so that it is of substantially conical form to wedge tightly into the covering sleeve 2. This sleeve may be provided on its exterior with any suitable grinding means. For instance, in Figs. 1 to 5 I have shown straight sharp-edged longitudinal ribs 3, in Figs. 7 and 8 the longitudinal ribs 4 on the sleeve are in the form of transversely curved corrugations, and in Fig. 9 I have shown suitable ribs 5 of spiral or herring-boned form. These three forms of ribs are merely typical of numerous grinding means with which the covering 2 may be provided. Moreover, it may be pointed out that this covering may either be of one piece form as shown for instance in Fig. 9, or may be constructed of two end sections 6 and 7, having interfitting circumferentially spaced lugs 8 on their abutting ends.

The ends of the covering sleeve 2 are provided with circumferentially spaced flat-sided lugs 9 which extend beyond the ends of the plug 1 and are of a radial width equal to the thickness of the covering sleeve 2. A pair of flat annular plates 10 are secured by cap screws or the like 11, to the ends of the Jordan plug 1, these plates being provided with circumferentially spaced peripheral lugs 12, which are snugly received between the lugs 9, the outer edges of said lugs 12 being flush with the peripheral edges of the lugs 9, while the outer sides of said lugs 12 are similarly flush with the adjacent sides of said lugs 9. The inner sides of the lugs 12 contact with the ends 90 of the covering sleeve 2, between the lugs 9, to hold said sleeve tightly upon the Jordan plug.

By employing the construction shown and described, a very simple and inexpensive means has been provided for detachably securing the covering sleeve in place and for establishing an effectual driving connection between this sleeve and the Jordan plug. The sleeve is tightly held upon the plug 105 against circumferential creeping as well as against endwise play, yet by removing the smaller of the plates 10, it will be seen that the covering 2 may be easily removed, whether it be formed of one or more sections.

When all parts are properly assembled I

prefer to lock the cap screws 11 in place by passing wires 14 through openings 15 in the heads of said screws. Other locking means could be employed if desired.

5 As excellent results may be obtained from the details disclosed, these details may well be followed. It is to be understood however, that within the scope of the invention as claimed, numerous minor changes may 10 be made.

I claim:

1. The combination with a Jordan plug of circular cross section; of a covering sleeve for said plug having circumferentially spaced lugs on its ends extending beyond the ends of said plug, and a pair of annular plates secured to the ends of said plug and having circumferentially spaced peripheral lugs snugly received between said 15 lugs of said sleeve.

2. The combination with a conical Jordan plug; of a tapered covering sleeve 20

snugly receiving said plug and having circumferentially spaced flat-sided lugs extending beyond the ends of said plug, a 25 pair of flat annular plates having circumferentially spaced flat-sided peripheral lugs snugly received between the lugs of said sleeve and having their outer edges flush with the outer surface of said sleeve, the 30 outer sides of the lugs of said plates being flush with the lugs of said sleeve, the inner sides of the lugs of said plates being in contact with the ends of the sleeve between the lugs of the latter.

3. A structure as specified in claim 2, said sleeve being transversely divided into a plurality of sections having interfitting circumferentially spaced lugs on their abutting ends.

In testimony whereof I have hereunto affixed my signature.

EDWIN A. STRATTMAN.
